UNITED STATES PATENT OFFICE

103,883

DESIGN FOR A TIRE PRESSURE INDICATOR OR SIMILAR ARTICLE

Peirce van Vleck, Washington, D. C.

Application December 11, 1936, Serial No. 66,489

Term of patent 7 years

To all whom it may concern:

Be it known that I, Peirce van Vleck, a citizen of the United States, residing at 5425 Connecticut Avenue, N. W., Washington, D. C., have invented a new, original, and ornamental Design for Tire Pressure Indicators or Similar Articles, of which the following is a specification, reference being had to the accompanying drawing, forming part thereof.

In the drawing,

Figure 1 is a side elevational view of a tire pressure indicator, showing my new design; and,

Figure 2 is an end elevational view, looking at Figure 1 from the left.

The design consists of a casing, as shown, in the front central portion of which is an indicator lens consisting of concentric contrastingly colored areas to consecutively indicate varying pressure conditions within the tires.

I claim:

The ornamental design for a tire pressure indicator or similar article, substantially as shown and described.

PEIRCE VAN VLECK.
